UNITED STATES PATENT OFFICE.

ARTHUR C. EASTWOOD, OF ENSLEY, ALABAMA, ASSIGNOR TO THE ELECTRIC CONTROLLER AND SUPPLY COMPANY, OF CLEVELAND, OHIO.

CONTROLLING-BRAKE FOR MOTORS.

SPECIFICATION forming part of Letters Patent No. 660,054, dated October 16, 1900.

Application filed May 14, 1900. Serial No. 16,635. (No model.)

To all whom it may concern:

Be it known that I, ARTHUR C. EASTWOOD, a citizen of the United States, and a resident of Ensley, Alabama, have invented certain 55

5 Improvements in Controlling-Brakes for Motors, of which the following is a specification.

My invention relates to certain improvements in controllers for electric motors.

I have shown my invention applied to the 10 controller for which a patent was granted to A. C. Dinkey on July 7, 1896, No. 563,575.

The object of the invention is to apply a braking force to a motor by means of connections on a controller which will make the 15 motor act as a generator, the speed being controlled by varying the resistance in circuit.

Referring to the accompanying drawings, 20 Figure 1 is a perspective view of my improved controller. Fig. 2 is a diagram view showing the wiring when my invention is used in connection with a Dinkey controller. Fig. 3 is a diagram view of a modification. Fig. 4 is a view showing diagrammatically the circuits 25 through the controller and motor when the controller-handle is so thrown as to change the motor to a generator.

H is the frame of the controller, having a cylindrical slate tablet H', to which the contacts 30 are secured.

I is the contact-arm, mounted on the shaft I', having its bearings in the frame, and this shaft is geared to an operating-lever J in a manner similar to that described in the 35 Dinkey patent, above referred to. There are two series of concentric contact plates or blocks, one mounted within the other, and on the arm are contact-fingers i i', which make contact with the plates or blocks.

40 B', B², B³, and B⁴ of the outer circle and B⁵ and B⁶ of the inner circle are the segments which are required by the brake. The necessary connections between these segments are made by the fingers of the controller-arm. No change in or addition to 45 these fingers is made necessary by the addition of my improved brake mechanism to the controller.

The blocks R' to R⁷, inclusive, represent 50 the resistance-blocks found on the Dinkey type of controller, while the blocks D' D² D³

D⁴ of the outer series and the blocks D⁵ D⁶ D⁷ D⁸ of the inner series are dead-blocks—that is, when the fingers of the controller-arm are on these blocks the motor is receiving no current and can "coast" under its own momentum. The plates C C are contact-plates, upon which the fingers of the contact-arm rest when covering any pair of the resistance-blocks. If, for instance, the controller-arm is 60 in the extreme position a b when it is desired to stop, resistance is cut in through the resistance-segments R' R², &c. When the segments D', D⁴, D⁵, and D⁸ are reached by the fingers of the contact-arm, the motor receives no current, as mentioned above, and coasts under its own momentum. As it moves into the next 65 position B' is connected to B⁵ and B⁴ to B⁶, as shown diagrammatically in Fig. 4. This connects the motor as a series generator, the connections being such that the current generated tends to "build up" the residual magnetism of the fields. This throws a load on the armature, and it comes to rest immediately or gradually as it is allowed to generate more 70 or less current. Following the controller-arm from the other extreme position c d to the horizontal position, it will be seen that B³ is now connected to B⁵ and B³ to B⁶. This reverses 75 the connections of the armature and fields; but since the armature is traveling in the opposite direction the electromotive force is also reversed, and hence the current traverses the field-coils in the same direction as before and the machine builds up as a generator. 80

For regulating the current generated, and hence the braking force, in the case of the trolley or hoist of a crane, where the momentum of the load is never very great, in place of connecting B³ to a it may be connected to 85 any of the resistance-segments R² R³, &c., thus throwing more or less resistance in the circuit.

I have found by experiment that the current generated in the above cases is so small 90 and of such short duration that the controller resistance is not perceptibly heated. Hence the whole arrangement can be made self-contained on the controller without the addition of separate resistance.

In the case of the bridge travel, where both 95 the speed and the momentum are high, a shunt

is automatically connected across the field-
terminals. By varying the resistance of this
shunt the fields are more or less highly ex-
cited and the current thus controlled. This
5 shunt is connected between D' and D³, and by
connecting D' and D² and D³ and D⁴ the same
shunt can be used going in either direction.
In this case the segments are so designed that
in one position of the arm the fingers make
10 contact on both D' and B' on one side and D⁴
and B⁴ on the other side and in the other po-
sition contact is made on B² and D² and B³
and D³. This is easily accomplished by cham-
fering the adjoining edges of the segments in
15 such a way that the fingers drop into the
groove thus formed. Thus it is seen that the
energy due to the momentum of the armature
and the load to which it is attached form, pri-
marily, the braking force. Hence no useful
20 power is expended in making the stop. The
braking force is applied directly to the arma-
ture, where it has the greatest advantage, and
is applied without the intervention of solen-
oids, brake-bands, or friction devices.
25 The device for applying the brake can be ap-
plied directly to the controller or starting-box
by means of which the motor is operated. The
motor is thus under the complete control of
one lever. No additional wires are necessary
30 between the motor and the controller.
In the case of a reversing-motor the seg-
ments and contact-fingers are arranged in
such a way that the armature is brought to
a stop before the current can be reversed
35 through it. Thus the possibility of "plugging"
the motor is precluded. By "plugging" is meant
the sudden reversal of the current in the armature. The heavy rush of
the current due to this and its consequent
40 bad effect upon the armature is well known.
This alone is an extremely-valuable advan-
tage which the device possesses. Its use as
a brake in connection with the controller puts
the motor under complete control, which, for
45 instance, in crane-service is of great value.
Equipped with my improvement the trolley
can be run out all the way at full speed, the

current shut off, and the trolley brought to a
full stop at the point desired.

In the case of a hoist where a solenoid and
brake-band are used it is impossible to make
a quick positive stop owing to the air which
the brake-band entrains between itself and
the brake-wheel. With the "controller-
brake" the stop can be made as quick and
55 decisive as desired.

When my invention is applied to a motor
running in one direction only, I design the
controller as shown in the diagram Fig. 3.

I claim as my invention—

1. The combination in a motor-controller,
of two series of concentrically-placed resist-
ance-blocks, a contact-arm having four sets
of fingers thereon constructed to bear on said
blocks, two series of brake-blocks placed
similarly to the resistance-blocks in the path
of the contact-arm, connected to the motor-
circuit and disconnected from the line, where-
by the motor is made to act as a series gen-
erator when running under its own momen-
tum, thus retarding the motion of the arma-
ture without using current from the line, sub-
stantially as described.

2. The combination in a motor-controller
of two concentrically-arranged series of con-
tact-pieces, a contact-arm and two sets of con-
tact-fingers thereon, movable over the con-
tact-pieces, said pieces consisting of resist-
ance points or blocks, brake-blocks and dead-
blocks, the dead-blocks intervening between
the resistance and the brake blocks and the
brake-blocks being connected to the motor-
circuit and not to the line, thereby short-cir-
cuiting the motor on itself when the said con-
tact-arm rests on the brake-blocks, substan-
tially as described.

In testimony whereof I have signed my
name to this specification in the presence of
two subscribing witnesses.

ARTHUR C. EASTWOOD.
